PARCEL BAG

Harold I. McMillan, Cohoes, N. Y., assignor to
 Cohoes Envelope Company, Inc., Cohoes, N. Y.,
 a corporation of New York

Application March 31, 1949, Serial No. 84,714

3 Claims. (Cl. 229—55)

1

My invention relates to parcel bags of the sort conveniently employed in retail establishments for wrapping merchandise. Inasmuch as each bag is ordinarily employed but once and is, in effect, given away without direct charge to the customer it is practically necessary to employ relatively inexpensive materials and construction in their manufacture.

In recent years determined efforts have been made to foster the use of paper bags for the carrying of articles hitherto generally wrapped and tied or sealed. Considerable difficulty has been encountered in connection with the development of bags suitable for the safe accommodation of articles of relatively large weight and volume, particularly asymmetrical objects such as shoes, items of hardware, and the like. The most common fault experienced with paper bags for such purposes has been the frequent tearing or rupture of the relatively weak paper of the bag in the vicinity of its bottom.

The most important object of my invention is effectively and inexpensively to reinforce the bottom area of a conventional paper bag.

Another object of the invention is to provide a paper bag having bottom reinforcement consonant with the requirement that the bag be so formed that it can be folded flat for shipment in stack formation.

An important feature of the invention resides in a bag having front and rear walls, a bottom, and a hinged panel or platform secured to one wall adjacent the bottom and so mounted that it is normally folded flat between and parallel to the front and rear walls but will automatically unfold with the expansion of the bag to assume an inclined position where it will first encounter an entering article and then be driven down by it until the panel comes to rest against the bottom of the bag. In the latter position the panel combines with the bag bottom to support the contained article.

These and other objects and features of the invention will be more readily understood and appreciated from the following detailed description of a preferred embodiment thereof selected for purposes of illustration and shown in the accompanying drawings, in which:

Fig. 1 is a view in side elevation of a bag constructed in accordance with my invention,

Fig. 2 is a view in cross-section along the line 2—2 of Fig. 1, and

Fig. 3 is a view in perspective of a fully opened bag.

As will appear in the drawing, the bag com-

2

prises essentially a long sheet of paper folded in the center to provide a front panel or wall 11, and a rear wall 10 secured together along their edges in an overlapped cemented joint. The 5 walls are creased and folded to form bellows side walls 13 and 14, while the bottom 12 is folded and creased to form a central fold line 25 and corner tucks effective to provide a conventional bellows type of bag structure.

10 The upper end portions of the bag walls 10 and 11 may, if desired, be subjected to any suitable processing resulting in the provision of carrying handles. For example, in the drawing I have shown the wall 10 as brought higher than the wall 11 to form a foldable protective cover flap 17, while both walls are patched with reinforcing material and cut to form conventional handle members 15 and 16.

What has thus far been described is entirely 20 conventional and merely illustrates one convenient form of bag structure to which the device of my invention may conveniently be applied.

The reinforcement of my invention includes a 25 flat rectangular panel or strip of satisfactorily stout paper or cardboard creased to form a center stiffener 20 bounded at each end by an integral flap or flange defined by a transverse crease. One flange 19, defined by the crease 21, is glued or cemented to the wall 11 in such relationship that the crease line 21 coincides with the crease line 24 at the corner between the bottom 12 and the wall 11. The remainder of the reinforcing member is unsecured and free to swing about the line 21 as a hinge.

30 As the bag is being made, the reinforcing member is cemented in place and then folded over to lie flat upon the wall 11, the free end flap 23 then being in the plane of the center piece 20 but ready to swing about its crease line 22. Bags 35 of this sort are ordinarily cut, folded, and cemented in one machine which discharges the flat bags sequentially into a bin or receiver in which they are stacked and jogged into neat bundles for shipment. The integral sections of the reinforcing member then lie flat upon and parallel to the side walls of the bag.

When a single bag is removed from its stack and partially opened as shown in Fig. 2, the center piece swings outwardly about the hinge or crease line 21 to diagonal position, while flange 23 also swings a trifle about the crease line 22 to lie flat on the wall 10. This action of the reinforcing member is the natural and automatic result of the resiliency inherent in most paper products.

When an article, such as a shoe, is introduced into the bag, it encounters the piece 29 and swings it out and down about the line 21 until the panel 26 comes to rest on the flat bottom of the bag. In the meantime, the flap 23 slides down the far wall 10 and also swings about the line 22 until it comes to rest perpendicular to the center piece 29. The reinforcing member is then U-shaped and spans the bottom 12.

In this condition it should be noted that the reinforcing member serves two functions. It combines with the bottom 12 to stiffen it and take the thrust and weight of the article in the bag and prevent rupture of the bottom. Moreover the two now-vertical flaps 19 and 23 protect the bottom areas of the side walls, easily absorbing the shearing stresses encountered particularly from articles wider than the bag bottom.

The width of the reinforcing member is not critical; as shown herein, it occupies the center half of the bag bottom, but it may be extended substantially to cover the entire bottom, if desired.

Having thus disclosed my invention, what I claim as new and desire to secure by Letters Patent of the United States is:

1. A collapsible bag comprising front, rear and gusseted side walls, a bottom, and a panel of relatively stiff resilient material having a width no greater than the distance between the inwardly extending gussets when the bag is in collapsed position creased to form an end flange secured to only one of said first two mentioned walls adjacent the bottom with the crease extending along the lower edge to which it is secured, said panel being folded upon itself about the crease in the collapsed position of the bag to be substantially flat between the walls thereof, the panel being sufficiently resilient to swing out and down automatically as the bag is opened and be forced against the bottom of the bag by the weight of an article inserted therein.

2. A collapsible bag comprising front and rear walls and a bottom, and a panel of relatively stiff resilient material creased adjacent one end to form a flange cemented to one of said walls adjacent the bottom with the crease extending

along the lower edge to which it is secured, said panel also being creased adjacent its free end to form a flange, the panel lying substantially flat entirely between the two walls in the collapsed position of the bag and folded upon itself about the first crease so that the free end flange bears resiliently upon the wall opposite, the panel being sufficiently resilient to automatically swing out and down as the bag is opened and come to rest upon the bottom of the bag as a U-shaped tray.

3. A collapsible bag comprising front, rear and gusseted sidewalls, a bottom and a panel of relatively stiff resilient material having a width no greater than the distance between the inwardly extending gussets when the bag is in collapsed position creased adjacent one end to form an end flange secured to only one of said first two mentioned walls adjacent the bottom with the crease extending along the lower edge to which it is secured, and creased adjacent the opposite end to form an intermediate portion equal to the width of the bottom and an end flange to engage the inner face of the opposite bag wall, the panel being folded upon itself about the first crease in the collapsed position of the bag to be substantially flat between the walls thereof, the panel being sufficiently resilient to swing out and down automatically as the bag is opened and be forced against the bottom of the bag by the weight of an article inserted therein.

HAROLD I. McMILLAN.
